UNITED STATES PATENT OFFICE.

SIEGFRIED BUDER, OF HALENSEE, NEAR BERLIN, GERMANY.

APPARATUS FOR USE IN THE CLEANING OF CARPETS AND THE LIKE BY SUCTION.

No. 859,914.

Specification of Letters Patent.

Patented July 16, 1907.

Application filed October 10, 1905. Serial No. 282,106.

To all whom it may concern:

Be it known that I, SIEGFRIED BUDER, a subject of the Emperor of Germany, residing at Halensee, near Berlin, Germany, have invented certain new and useful Improvements in or Relating to Apparatus for Use in the Cleaning of Carpets and the Like by Suction, of which the following is a specification.

This invention relates to devices in the nature of air pumps especially designed for exhausting air through 10 pipes for cleaning purposes, such as the pneumatic system of removing the dust and dirt from the interior of houses and from the carpets and furniture therein.

The invention especially relates to a form of air pump, and has for its principal object to provide means 15 whereby the cleansing of the apparatus is facilitated, the particles of dust and dirt and refuse matter drawn into the various parts of the pump being readily accessible and removable.

In the accompanying drawing showing an embodiment 20 of my invention, Figure 1 is a vertical section with the parts in normal position, and Fig. 2 a similar view with certain parts disconnected for the purpose of cleansing. Fig. 3 is a section on the line A—B indicated in Fig. 1.

25 A pump device in the nature of accordion bellows 1, with top and bottom members 2 and 3, is arranged in a vertical cylinder 4, having a top 5 and a bottom 6. The top 5 is removably secured by means of link screw members 7 and 8, a packing ring 11 being interposed to make the top air-tight. The bottom 6 is similarly secured to the cylinder 4 by link bolts 9 and 10, with the interposition of an air-tight packing ring 12. The bottom member 3 of the bellows, which is of less diameter than the bottom 6 of the cylinder, is rigidly secured 30 thereto in any suitable manner. A flap valve 13 closes an admission port 14 passing through the combined bottom member 3 and 6, the valve automatically closing when the pressure in the bellows exceeds that in the port 14. An outlet port 16 in the bottom member 40 is controlled by a flap valve 15, permitting escape of the air in the bellows but preventing admission of air thereto through this port. A port 17 in the bottom member 6 of the cylinder serves to admit air to the cylinder, but air is prevented from escaping from this 45 port by flap valve 17. A chest 22 surrounds these admission ports 13 and 17, and connects with the suction pipe 21. Another port 20 is formed in the bottom 6 of the cylinder that is controlled by a flap valve 19 preventing admission into the cylinder through this port.

50 The ports 20 and 16 open into a valve chest 24, connecting with an outlet pipe 23. The bottom of the bellows is provided with an aperture 26 that is normally closed by conical plug 25, but when it is desired to clean out the bellows to remove particles of dust and 55 other matter, this plug is withdrawn.

A rod 29 is secured to the bellows head 2 by nuts 27

and 28, and passes through the cylinder head 5, being tightly fitted therein by a packing sleeve 31. The upper end of the rod 29 has a transverse slotted portion 30 into which projects a pin 35 on a lever 34. The lever 60 is pivotally supported on a bracket 33 secured to the cylinder 4 at 32. A number of standards 36 secured to the cylinder 4 serve to support the device with the cylinder a considerable distance removed from the floor or ground. 65

The operation of the device is as follows: The oscillation of handle lever 34 will reciprocate the rod 29 and bellows head 2, which will compress and expand the bellows, the bottom members 3 and 6 being locked in the position shown in Fig. 1. When the bellows is 70 compressed and the head 2 advanced towards the head 3, the air will be driven out of the bellows through port 16 and escape through pipe 23. This compression of the bellows will tend to produce a vacuum in the cylinder 4 and the air will be sucked in through port 18 75 raising valve 17, which will suck air in through the pipe 21. Upon the cylinder head 2 rising, the air will be drawn into the bellows through port 14, the flap valve 13 opening, which will also draw air in through pipe 21. This expansion of the bellows will compress 80 the air in the cylinder 4 and it will be forced out through port 20, by the opening of valve 19, the air passing out through pipe 23. By these means a double acting pump is provided in which the air will be constantly sucked in through pipe 21 and expelled through 85 pipe 23. But when such apparatus is used for pneumatic cleaning, a large amount of dust and refuse matter will be drawn in with the air, that will tend to collect both in the bellows and in the cylinder. Thereupon, link screws 9 and 10 are loosened and swung 90 away from the bottom member of the cylinder and bellows, and the bellows is permitted to lower to the position indicated in Fig. 2, its downward position being limited by engagement of the lever 34 with the top 5. This will permit the ready cleansing of the bottom 95 of the cylinder around the bellows and also of the valves in the bottom member. The plug 25 in the bellows is removed and thereby the foreign matter in the bellows around its lower end is readily removable.

Having thus described my invention, I claim:

1. In a device of the character described, the combination of a cylinder, a bellows located in the cylinder and having its bottom secured to the bottom of the cylinder, inlet and outlet ports in said bottom for the bellows, a valve controlling each of said ports, an inlet and an outlet 105 port for the cylinder that are located in said bottom, a valve controlling each of said latter ports, said bottom member of the cylinder and bellows being removably secured to the cylinder.

2. In a device of the character described, the combination of a cylinder, a bellows located in the cylinder and having its bottom secured to the bottom of the cylinder, inlet and outlet ports in said bottom for the bellows, a valve controlling each of said ports, an inlet and an outlet 110

port for the cylinder that are located in said bottom, a valve controlling each of said latter ports, said bottom member of the cylinder and bellows being removably secured to the cylinder, the bellows being provided with a 5 removable plug in its bottom for cleaning purposes.

3. In a device of the character described, the combination of a cylinder, a bellows operable in the cylinder and having its bottom member of less area than the bottom of the cylinder with such bottom members secured together, 10 an inlet port through said bottom member to the bellows, an admission valve controlling said port, an inlet port for the cylinder located in the said bottom and in proximity to said inlet port for the bellows, an admission valve controlling said latter port, a valve chest surrounding said 15 inlets, a pipe connecting with said valve chest, an outlet port for the bellows passing through said bottom, an outlet port for the cylinder located in proximity to said outlet port and passing through the bottom and a valve controlling each of said outlet ports, a valve chest surrounding said outlet ports on the bottom of the cylinder, a pipe 20 connecting with said valve chest, and link screws for removably securing said bottom member and the cylinder.

4. In a device of the character described, the combination of a cylinder, a bellows located in the cylinder and having its bottom secured to the bottom of the cylinder, 25 inlet and outlet ports in said bottom for the bellows, a valve controlling each of said ports, an inlet and an outlet port for the cylinder that are located in said bottom, a valve controlling each of said latter ports, said bottom 30 member of the cylinder and bellows being removably secured to the cylinder, a rod secured to the upper end of said bellows and projecting through the upper end of the

cylinder, a transverse slotted member on said rod, and a pivoted lever having a pin operating in said slotted member for reciprocating said rod to operate the bellows.

35

5. In a device of the character described, the combination of a cylinder, a bellows operable in the cylinder and having its bottom member of less area than the bottom of the cylinder with such bottom members secured together, 40 an inlet port through said bottom member to the bellows, an admission valve controlling said port, an inlet port for the cylinder located in the said bottom and in proximity to said inlet port for the bellows, an admission valve controlling said latter port, a valve chest surrounding the said inlets, a pipe connecting with said valve chest, an 45 outlet port for the bellows passing through said bottom, an outlet port for the cylinder located in proximity to said outlet port and passing through the bottom and a valve controlling each of said outlet ports, a valve chest surrounding said outlet ports on the bottom of the cylinder, a pipe connecting with said valve chest, link screws for removably securing said bottom member and the cylinder, 50 a rod secured to the upper end of said bellows and projecting through the upper end of the cylinder, a transverse slotted member on said rod, and a pivoted lever having a pin operating in said slotted member for reciprocating said rod to operate the bellows.

In testimony whereof I have hereunto set my hand in the presence of the undersigned witnesses, at Berlin, Germany, this 27th day of September 1905.

SIEGFRIED BUDER.
